(57) **CLAIM**

The ornamental design for a low lift truck, as shown.

DESCRIPTION

FIG. 1 is a front perspective view from the right side of the low lift truck; and,

FIG. 2 is a rear perspective view from the right side of the low lift truck.

The surface(s) or portion(s) of the article not shown in the drawing or described in the specification form(s) no part of the claimed design.
